UNITED STATES PATENT OFFICE.

CHARLES J. FOLLMER, OF NEW YORK, N. Y.

DESIGN FOR A PARASOL.

47,690.

Specification for Design. Patented Aug. 10, 1915.

Application filed November 21, 1914. Serial No. 873,406. Term of patent 14 years.

To all whom it may concern:

Be it known that I, CHARLES J. FOLLMER, a citizen of the United States, residing at New York, in the county of New York and State of New York, have invented a new, original, and ornamental Design for Parasols, of which the following is a specification, reference being had to the accompanying drawing, forming a part thereof.

In the drawing, Figure 1 shows an eleva-

tion of a parasol of my design, and Fig. 2 is a top view thereof, the sections forming the cover being gathered as indicated.

I claim:—

The ornamental design for a parasol as shown and described.

CHARLES J. FOLLMER.
